LIQUID FUEL BURNER

Albert R. Thomas, Evansville, Ind., assignor to
 Servel, Inc., New York, N. Y., a corporation of
 Delaware

Application September 3, 1937, Serial No. 162,230

1 Claim. (Cl. 62—5)

My invention relates to liquid fuel burners and it is an object of the invention to provide an improved burner which is readily refueled, simply controlled, and quickly accessible for servicing. 5 The drawings show a burner for use with a heat operated refrigerator. The burner is pivoted so that it may be swung outside of a refrigerator cabinet for cleaning or other servicing. An inverted bottle liquid fuel reservoir is provided 10 with an automatic valve permitting ready refueling. A fountain feed and flow control valve provides a simple control. This combination, its operation, and utility are set forth with more particularity in the following description which 15 makes reference to the accompanying drawings in which:

Fig. 1 shows the lower part of a refrigerator provided with an absorption type refrigeration apparatus heated by a burner embodying the invention; 20

Fig. 2 is a sectional view of the burner assembly taken on line 2—2 in Fig. 3;

Fig. 3 is a sectional view taken on line 3—3 in Fig. 1 showing a side view of the burner assembly in the lower part of the refrigerator; and

Fig. 4 is a top plan view of the burner assembly showing the burner swung outside of the refrigerator cabinet.

30 A refrigerator cabinet 10 has a lower apparatus compartment 11 accessible at the front by means of a door 12. The refrigerator is provided with an absorption type refrigeration apparatus including a generator 13 located in the apparatus compartment 11. The generator includes a tank 14 and heating and circulating coil 15 surrounded by thermal insulation 16. The parts of the refrigeration apparatus shown and mentioned in this specification are only illustrative of the heat input portion of any desired type of absorption refrigerator system. 40

A burner assembly includes an inverted bottle reservoir 17, a cup 18, a conduit arm 19, and a burner well 20. The burner well 20 is an annular chamber open at the top and closed at the bottom. A metal gauze wick 21, also ring shaped, is located in the well 20. A perforated cylinder 22 is located concentrically within the upper part of the burner well 20 and it extends appreciably above the open top of the well. The upper end of the perforated cylinder 22 is closed and the lower end is open. The burner well 20 is fastened on one end of a conduit 19. The other end of conduit 19 is connected to the cup 18. Conduit 19 not only supports the burner well but also

provides communication between the lower part of the cup 18 and the lower part of the well 20.

Surrounding the burner well 20 is a cylindrical shield 23 open at the top and bottom. Below the bottom of the shield 23 and spaced therefrom is a dished shield 24 having an opening 25 in the bottom and substantially centrally thereof. The burner well 20 is directly above the opening 25. The shields 23 and 24 are secured together with the burner well on the conduit 19. In Figs. 1, 2 and 3 the burner well 20 is shown located in its operative position directly beneath the lower end of the generator 13. In the refrigerator cabinet 10, there is a flat shield plate 26 located directly below the opening 25 in the shield 24 when the burner well 20 is located beneath the generator.

The cup 18 is formed on the bottom to provide a bearing plate 27 and a spindle 28. A bracket 29 mounted on the refrigerator is provided with a bearing 30 which receives the cup spindle 28. The spindle 28 is turnable in the bearing 30 so that the burner well 20 with its shields 23 and 24 may be swung, when the apparatus compartment door 12 is open, from the position shown in Figs. 1, 2, and 3 to the position shown in Fig. 4. In this position, the burner well is fully accessible for trimming the wick, cleaning, or other servicing.

Above the cup 18 is a spring clip bracket 31 or other suitable device for holding the inverted bottle 17. The bottle 17 is provided with a cap 32 (see Fig. 2) which may be screwed on or unscrewed from the neck of the bottle. The cap 32 is provided with a valve 33 on a plunger 34. The valve 33 is urged to its closed position by a spring 35. When the bottle 17 is inverted into the cup 18, the weight of the bottle causes the plunger 34 to contact the bottom of the cup and hold the valve 33 open against the action of the spring 35.

The bottle 17 and cup 18 provide a fountain feed for liquid fuel from the bottle into the cup.

In the conduit arm 19 is a valve 36 which is adjusted by a knob 37 for regulating flow of liquid from the cup 18 through conduit 19 to the burner well 20. The level of liquid is substantially constant in the cup 18 and at starting the level of liquid in the burner well 20 is the same as the level in cup 18. During operation of the burner, the level of liquid in the burner well 20 is at or below the level of liquid in the cup 18 depending upon the adjustment of the valve 36 which controls flow of liquid through conduit 19.

To start, the bottle 17 containing liquid fuel,

such as kerosene, is inverted into the cup 18 and secured in the spring clips 31. The burner well 20 is revolved through the door opening to the position shown in Fig. 4. In this position, a flame 5 is ignited at the upper edge of the wick 21. The burner is then turned back into its position under the generator and the valve 36 adjusted for the desired rate of flow of liquid fuel through conduit 19 and thereby the desired flame when the burner 10 operation becomes steady. Air is supplied for combustion through two paths as indicated by arrows in Fig. 2. In one path, air flows above plate 26 into the opening 25 at the bottom of shield 24 and thence upward through the annular burner well 20 and perforated cylinder 22. Air 15 also flows upward around the outside of the burner well 20 and enters around the top of the dished shield 24, flowing downward between the shields 23 and 24 and thence upward to the burner 20 flame. This tortuous air flow results in steady burner operation unaffected by drafts and the like.

If the refrigeration apparatus is of a continuous type, the reservoir 17 may be of any desired 25 size since it need be refilled only when substantially empty. If the refrigeration apparatus is of an intermittent type, the intermittent burner operation may be obtained with a large reservoir by utilizing the valve 36 to shut off flow of liquid 30 fuel at the desired end of the generating period. However, with this type of system, it will be found

advantageous to provide a small bottle 17, or fill the bottle only with a desired quantity of liquid so that the amount of fuel is just sufficient for supplying the burner for the length of a desired heating or generating period. With this 5 type of system, the burner has to be intermittently lighted as, for instance, once each day. This task is simplified by being able to merely turn the burner well outside of the apparatus compartment where the burner is readily accessible for lighting. 10

What is claimed is:

The combination with a refrigerator having a cooling compartment and an apparatus compartment and heat operated refrigeration apparatus 15 including a generator having a flue, of heating apparatus utilizing vaporization and combustion of a fuel oil and including a revoluble fuel reservoir mounted in said apparatus compartment, a conduit for fuel connected to said reservoir and projecting laterally therefrom, a burner supported on the other end of said conduit and connected thereto, an air flue around said burner and also mounted on said conduit, said conduit being 20 of such length so that said burner flue forms a prolongation of said generator flue, and said burner and its flue may be swung horizontally to a position outside of said apparatus compartment for servicing of the burner. 25
